UNITED STATES PATENT OFFICE

CHRISTIAN H. HANSEN, OF WASHINGTON, DISTRICT OF COLUMBIA.

UNDERGROUND TELEGRAPH-LINE.

SPECIFICATION forming part of Letters Patent No. 267,883, dated November 21, 1882.

Application filed November 29, 1881. (No model.)

To all whom it may concern:

Be it known that I, CHRISTIAN H. HANSEN, a citizen of the United States, residing at Washington, in the county of Washington and District of Columbia, have invented certain new and useful Improvements in Underground Telegraph-Lines, of which the following is a specification, reference being had therein to the accompanying drawings, in which—

10 Figure 1 is a vertical cross-section, and Fig. 2 is a longitudinal vertical sectional view.

Similar letters of reference indicate corresponding parts in both figures.

This invention relates to underground telegraph-lines, and it contemplates certain improvements in the construction of the same, having for their objects reduction in the cost of laying such lines, affording facilities for the inspection and repair (when necessary) of the 15 wires, and an arrangement whereby the wires of the line, while occupying but small space, shall be well separated and isolated, substantially as will be hereinafter more fully described, and particularly pointed out in the claim.

20 Referring to the drawings hereto annexed, A represents an inverted-trough-shaped or semi-cylindrical shell constituting one of the supports or holders for the wires of my improved telegraph-line. This shell or support, which may be of any suitable dimensions, I 25 prefer to make of terra-cotta, which, in order to render it hard, smooth, and impervious to moisture, should be glazed and baked hard. I would have it understood, however, that any 30 other suitable material—such as unglazed terra-cotta, clay, glass, wood, or any other compound material—may be employed in the construction without deviating from the principles of my invention.

35 Upon the outer or convex surface of the shell or inverted trough (as it may be designated) A is formed a series of longitudinal grooves, B, of sufficient depth to receive and hold the telegraph-wires without danger of their being 40 displaced or coming in contact with each other. The edges of the supports are preferably provided with outward-projecting flanges C, but this is not necessary or essential.

45 D represent a second series of supports, constructed substantially like the supports A— 50 that is to say, inverted-trough-shaped—and

provided upon their outer or convex sides with longitudinal grooves for the support of wires. They may also be provided at their lower edges with flanges E, by which they may be supported upon the flanges C of the supports A, over which they are constructed to fit, as clearly shown in Fig. 1 of the drawings; but said flanges may be omitted, as they perform no important or essential function.

55 Additional tiers or strata of supports may in practice be employed in the construction of my improved telegraph-lines, but in the drawings hereto annexed I have shown only the two A and D, just described, this being sufficient 60 in order to illustrate the principle of my invention. The uppermost tier or series of supports is covered by a series of caps, F, the edges of which may be flanged or not, as may be desired. One end of each of the caps F may also 65 be provided with a flange overlapping the unflanged end of the cap next adjoining.

70 The method of laying my improved telegraph-lines is preferably as follows: A trench of suitable dimensions is prepared and provided with a floor or base, G, of asphalt, concrete, or other suitable material, or this may be omitted and the bottom of the trench simply tamped hard. In the bottom of this trench the supports A are laid, in a longitudinal row, 75 a distance apart somewhat less than the length of the supports D. The wires, which are denoted by letter H, are then placed in position in the grooves B. When glazed terra-cotta is used in the construction of the supports this 80 will be found sufficient to isolate the wires, and ordinary galvanized-iron wires may be used instead of the far more expensive insulated wires usually employed in the construction of underground-lines. Covering-caps F may 85 now be placed directly over the supports A and the trench filled up; but when a second tier or series of supports is necessary, in order to accommodate the number of wires, these supports D are placed over and supported upon the ends 90 of the supports A, as clearly shown in Fig. 2 of the drawings. The upper wires, which are denoted by I, are then placed in position. By this arrangement it will be observed that when the 95 covering-caps are removed the wires H and I are all exposed to view, and any one of them may be readily reached without disturbing the

others. A great saving of material is also effected, which of course is an item of very considerable importance. Additional courses or strata of supports may be added before the 5 covering-caps are placed in position. Such courses or strata are to be arranged in a similar manner to that just described, and while of course the lower strata are thereby covered out of sight they may easily be reached at 10 any particular point, without disturbing the upper wires, by simply sliding the upper supports aside until the wire or wires sought for are uncovered.

While I have in the foregoing described the 15 supports as being semi-cylindrical in shape, I would have it distinctly understood that I do not wish to confine myself to this, or to any particular shape. The lowermost supports need not be concave or hollow upon the under 20 side. They may be solid or massive, and this may be found desirable when a number of courses or series of supports are to be used. Nor need their outer grooved sides be semi-circular in cross-section. They may be angular, 25 or of any desired shape, always provided, however, that their sides should slope down to their edges in order that all the wires used may be fully or sufficiently exposed to view when uncovered. As for the supports constituting the upper strata, it is only necessary or 30 desirable that their under sides should conform in shape to the upper sides of those next below, their upper sides sloping down to the edges, as stated.

As for the method of laying the line, the 35 construction of the trench is quite immaterial. The covering-caps need not be covered up with soil or dirt, as they may be made of sufficient strength and so arranged as to afford adequate protection; and while, for many reasons, 40 I consider the method of laying the courses of supports herein described to be preferable, I do not wish to confine myself to the same, and the supports forming each course may be laid close together, or any desired distance 45 apart.

Having thus described my invention, I claim and desire to secure by Letters Patent of the United States—

In a conduit for electric wires, the combination, with the covers F, of two or more series of longitudinally-grooved and hollow inverted-trough-shaped supports, arranged one within the other, as described, the supports of the same series being placed at some distance 55 apart, so that the upper series may be slid aside, while still sustaining the wires resting upon them, to uncover the wires resting on the series below, substantially as set forth.

In testimony whereof I affix my signature in 60 presence of two witnesses.

CHRISTIAN H. HANSEN.
